UNITED STATES PATENT OFFICE.

JOSEF WESOTY, OF KENOSHA, WISCONSIN.

FAN ATTACHMENT FOR ROCKING-CHAIRS.

1,256,962.

Specification of Letters Patent. Patented Feb. 19, 1918.

Application filed March 2, 1917. Serial No. 152,147.

To all whom it may concern:

Be it known that I, JOSEF WESOTY, a subject of the Czar of Russia, resident of Kenosha, county of Kenosha and State of Wisconsin, have invented certain new and useful Improvements in Fan Attachments for Rocking-Chairs, of which the following is a specification.

This invention relates to improvements in rocking chairs and has as its principal object the provision of means whereby air currents may be produced and delivered upon the person using the chair.

Another object is to provide means which operate automatically and without any physical effort on the part of the user.

These objects are attained by the novel design, construction and combination of parts hereafter described and shown in the accompanying drawings, forming a material part of this specification, and in which:

Figure 1 is a perspective view showing a chair in which the invention is embodied.

Fig. 2 is an enlarged vertical sectional view taken through the rocker and chair supports substantially on line 2—2 of Fig. 1.

Fig. 3 is a perspective view of an applicator or head, and

Fig. 4 is a sectional view taken on line 4—4 of Fig. 2.

The chair shown is to all appearances that of ordinary construction except that on one side the rocker 10 has engaged with it a similarly shaped additional hollow rocker element 11, the reinforcements, 12 and 13, of the legs on the same side also being hollow.

In the recess 15 in the element 11 is a lever 16 pivoted at its center upon the pin 17 which extends through the side of the rocker, the lever having equal arms and carrying pins 18 and 19 at its extremities, respectively at the front and rear of the chair, and with which are engaged vertical rods 20 and 21 operating in the spaces 22

and 23, the rods being bent at their upper ends 24 and 25 where they are attached to the lower elements 26 and 27 of bellows 28 and 29, engaged directly with the lower side of the chair seat 30, which is supported by the four legs in an obvious manner.

Extending downwardly and outwardly through the lower surface of the rocker element 11 are two projections 32, the same being operable in the slot 33 formed in the bottom of the rocker and in such manner that as the chair is rocked forward the rod 20 will be pressed upwardly compressing the bellows 28, and when the chair is rocked backward the projection at the opposite end of the lever raises the rod 21 compressing the bellows 29 which are provided with inlet valves 35 upon their lower sides and outlet pipes 36 upon their upper sides, which may be led to any desired point as into the header 38 in the back of the chair or similar headers arranged upon the arms or other convenient point so as to deliver a current of air upon the person sitting in the chair.

Thus without effort a person may, in using the chair and giving it rocking motion, be able to produce a current of air which will drive away flies and produce a cooling blast rendering the user comfortable.

Having thus described my invention, what I claim as new, and desire to secure by Letters Patent, is:

In a chair of the class described, the combination with a hollow rocker, and a pair of hollow legs, of a lever mounted to oscillate therein, projections extending downward from said lever through said rocker, arms extending upward from the ends of said lever through the legs of the chair, a pair of bellows having reciprocable heads, said heads being engaged with said arms, and pipes adapted to convey away the air currents therefrom.

In testimony whereof I have affixed my signature this 10th day of February, 1917.

JOSEF WESOTY.
